US00D936946S

(12) **United States Design Patent** (10) **Patent No.:** **US D936,946 S**
(45) **Date of Patent:** **** Nov. 30, 2021**

(54) **INSOLE**

(71) Applicant: **Reckitt Benckiser Health Limited**,
Slough (GB)

(72) Inventors: **Zakaria Baig**, Slough (GB); **Olga Dabrowska**, Slough (GB); **Daniel Edmondson**, Hull (GB); **Christian Generalis**, Hull (GB); **Samantha Louise Horrocks**, Hull (GB); **Dilan Fernando**, Colombo (LK); **Sahan Fernando**, Colombo (LK); **Rajeev Ganapathy**, Colombo (LK); **Habeebulah Illiyas**, Colombo (LK); **Sanuja Jayathilake**, Colombo (LK); **Christopher Nester**, Salford (GB); **Yasovarman Perippanayagam**, Colombo (LK); **Ben Samarasinghe**, Colombo (LK); **Buddika Sandaruwan**, Colombo (LK); **Madusha De Silva**, Colombo (LK)

(73) Assignee: **Scholl's Wellness Company Limited**,
London (GB)

(**) Term: **15 Years**

(21) Appl. No.: **29/729,231**

(22) Filed: **Mar. 25, 2020**

(30) **Foreign Application Priority Data**

Sep. 26, 2019 (EM) 006934253-0004

(51) **LOC (13) Cl.** **02-04**
